UNITED STATES PATENT OFFICE.

PAUL E. JOHNSON, OF CHICAGO, ILLINOIS, ASSIGNOR TO PAUL E. JOHNSON, INC., OF CHICAGO, ILLINOIS, A CORPORATION OF ILLINOIS.

DESIGN FOR A REFLECTOR HEAD FOR THERAPEUTIC LAMPS.

Application filed August 15, 1927. Serial No. 23,101. Term of patent 14 years.

To all whom it may concern:

Be it known that I, PAUL E. JOHNSON, a citizen of the United States, residing at Chicago, county of Cook, State of Illinois, have invented a new, original, and ornamental Design for a Reflector Head for Therapeutic Lamps, of which the following is a specification, reference being had to the accompanying drawing, forming a part hereof.

The figure is an elevational view of a reflector head for therapeutic lamps embodying my new design.

I claim:

The ornamental design for a reflector head for therapeutic lamps, as shown.

PAUL E. JOHNSON.
